FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPE-BAR AND TYPOGRAPHIC FORM

No. 862,511.

Specification of Letters Patent.

Patented Aug. 6, 1907.

Application filed August 29, 1901. Serial No. 73,640.

To all whom it may concern:

Be it known that I, FRANCIS H. RICHARDS, a citizen of the United States, residing at Hartford, in the county of Hartford and State of Connecticut, have invented 5 certain new and useful Improvements in Type-Bars and Typographic Forms, of which the following is a specification.

This invention pertains to the manufacture of type-bars, sometimes designated as linotypes, and to typographic forms, and it has for an object to provide a construction for typebars enabling them to be readily locked into a typographic form, when a number of the bars are assembled to make up such a form.

In carrying my present improvements into practice 15 each typebar, in whatever manner the same may be produced, will be so constructed at its end portions as to adapt it to engage with a member insertible into place for the purpose of securing the typebars, one to the other, when a number of the same are assembled; 20 and according to a further feature of the invention this member may be so constructed as to enable adjacent columns to be securely connected, one to the other, when the columns of composition are arranged side by side in building up a so called "large" form.

25 In the drawing accompanying the present specification, Figure 1 is a perspective view of a number of columns of composition, each comprising a series of individual typebars disposed side by side and locked, the several bars in the columns with each other, and the 30 several columns to one another, by means embodying the present improvements. Fig. 2 is a perspective view of a typebar so constructed as to enable the same to be connected or locked to other bars in the column of which it constitutes an element. Fig. 3 is a similar 35 view of a locking-strip or bar for connecting the several typebars of a column together, and also adjacent columns of such bars one to the other. Fig. 4 is a perspective view of a corner section of a chase or supporting frame for inclosing a typographic form setting forth a 40 construction of such chase whereby the several columns may be locked to the frame by means of the locking-strip illustrated in Fig. 3. Figs. 5, 6, and 7 are views similar to Figs. 1, 2, and 3, respectively, illustrating a 45 modified form of locking-strip, and showing a typebar construction adapting the bar to be engaged with such modified form of strip and Fig. 8 is a perspective view of the bar shown in Fig. 7, but looking at this from the other end.

Similar characters of reference designate correspond- 50 ing parts in all the figures.

For the purpose of enabling a typebar to be connected with other typobars in the column of assembled bars; I so form each bar, in carrying the present improvements into practice, as to enable it to be engaged by a 55 properly-formed locking member, insertible into place

and when so placed extending transversely to the line of length of the individual bars at the side of the column thereof. This interlocking of the bars, one with the other is therefore effected by providing a suitably formed locking member which extends from end to end 60 of the column at the ends of the assembled bars, it being in the nature of a locking-strip adapted to engage with the suitably-formed end portions of the bars. This engagement of the bars may obviously be effected in various ways by varying the construction of the locking- 65 strip and correspondingly varying the counterpart construction of the bars.

In the construction set forth in Figs. 1 to 3, inclusive, and in which figures the typebars are designated in a general way by B, each bar is provided with a trans- 70 verse notch or slot such, for instance as 2, and the locking-piece C is provided with a rib or tongue 3 of corresponding cross-sectional outline, adapting the tongue or rib to enter the notch in each bar. Shoulders are thus formed, which when a series of bars are mutually interlocked preclude the movement of each bar upward from the face of the form and also prevent its dropping out of place when the form is lifted up. Constructed in this manner it is evident that when the bars are assembled side by side in building up a column with 80 their notches in alignment, the locking-strip may be slid into place lengthwise of the column with the locking-tongue in engagement with such notches.

Where columns of composed matter are arranged side by side an extension of the principle involved in the 85 described construction may be adapted whereby not only will the bars of the respective columns be locked together but each column of composition will be locked to the column by the side of which it is disposed. The construction for effecting the connection of the bars together and of the adjacent columns one with the other may be similar to that already described, a rib or tongue 3 the same in form as the one referred to being provided on the opposite side of the locking-strip C to render this 90 strip interchangeable, end for end, the strip engaging 95 with notches 2 on the continuous ends of the bars in the adjacent column which notches will evidently, therefore, be similar in form to the first mentioned notches when the ribs are made as described. I have also shown the locking-strip as being adapted to the purposes of the so-called column rule, the upper edge of the strip being beveled, see 4, and terminating in the plane of the impression-face of the assembled typebars. Of course, the thickness of the locking-strip may be varied depending upon the desired proximity of the two columns, one to the other.

The usual supporting or bed-plate is designated by D; while the series of columns may be inclosed in a chase or frame, designated in a general way by E, and if desired the form may be locked to the chase. 110

When the bars and columns are connected with each other by the means herein shown and described, each locking-strip for the purpose of locking the form to the chase may be provided with an end projection 5 adapted to enter a corresponding socket 5' in one of the members of the chase, while that member which extends parallel with the strips when the latter are slipped into place may be channeled, see 6, to engage with the rib of the locking-strip in contact with such member. Instead, however, of making the construction of each end portion of a typebar analogous to the construction of the opposite end a form of locking-strip may be employed as set forth in Fig. 7, in which the locking-strip C' is provided on one side with a rib or feather 3' similar to the rib 3 of the strip C, while on the opposite side the strip is channeled or grooved, see 7, to engage with the bars. The bars will of course have a proper counterpart structure, consisting of a projection 8 at one end of each bar, while the opposite end of the latter is recessed or notched, see 9, to engage with the rib 3' of the adjacent strip. This locking-strip C' may, as before, constitute a column rule being beveled similarly to the strip C to form a rule 4. The strip may be provided at its ends with tenons 5'. The sustaining chase E' may also have upon one side a rib 10 for engaging with the channel 7 in the locking-strip which is in contact with that side when the form is made up; this latter chase may also have mortises (not shown) for engaging with the tenons on the ends of the locking-strip C', as described with reference to the chase E.

When constructed in the manner set forth a convenient means is provided, whereby the various members may be securely connected together and to the chase or sustaining frame by simply sliding the locking-strip into place when the columns have been assembled and placed in position yet enabling the typebars to be readily separated from each other upon withdrawing the locking-strips from their positions.

Having described my invention, I claim—

1. In a typographic form, the combination with a chase, of a locking-strip engaging at opposite ends with the chase, and a series of assembled typebars held in position by the locking-strip, one of the members having notches and the other member having a rib engaging with the notches.
2. In a typographic form, the combination with a chase, of a locking-strip engaging at opposite ends with the chase, and a series of typebars on opposite sides of the locking-

strip, the typebars having notches and the locking-strip having ribs engaging with the notches. 50

3. In a typographic form, the combination with a chase, of a locking strip engaging at opposite ends with the chase and also at one of its sides therewith, and a series of typebars with the ends of which the locking strip also engages. 55

4. The combination with a chase, of a locking-strip: typebars disposed on opposite sides thereof, the chase having notches, the typebars having notches and the locking-strip a rib at each side engaging with the notches of the bars, and a rib at each end engaging with the notches in the chase. 60

5. In a typographic form, the combination with a chase or supporting frame, of a locking strip engaged therewith along each side, and a locking strip disposed therebetween and engaged with the chase, and a number of series of typebars held in position by the locking strips by means of notches and ribs carried by the respective parts. 65

6. In a typographic form, the combination with a chase, of a locking-strip engaging at opposite ends with the chase, and a series of typebars on opposite sides of the locking-strip, the typebars and the chase having notches and the locking-strip having ribs engaging with the notches. 70

7. A typographic form comprising a chase, assembled typebars, a number of locking strips engaging at opposite ends with the chase and upon the sides with the ends of typebars by means of notches and mating ribs. 75

8. A typographic form comprising a chase, assembled typebars, a number of locking strips engaging at opposite ends with the chase and upon the sides with the series of typebars, the strips and chase interlocking, and the series of typebars and the strips interlocking. 80

9. In a typographic form the combination with a chase having channels at ends and sides, of a strip having a column rule along its edge, a rib along one side, a groove along the other side, and tenons at its ends, the ribs and tenons to fit the channels in the chase, a number of series of assembled typebars having projections and grooves to mate with the ribs. 85

10. A typographic form comprising a chase, assembled typebars, a number of locking strips engaging at opposite ends with the chase and upon the sides respectively with the chase and with the series of typebars, the strips and chase interlocking and the series of typebars and the strips interlocking. 90

11. In a typographic form, the combination with a chase having locking means at its ends and sides, of a locking strip engaging the locking means at opposite ends of the chase, typebars having locking means at each end and disposed on and locked with respect to the sides of said locking strip, locking strips engaging the locking means at the sides of the chase and the locking means on the contiguous ends of the typebars. 100
